[57] CLAIM

The ornamental design for a housing for an electronic
stimulator, as shown and described.

DESCRIPTION

FIG. 1 is a perspective view of a housing for an elec-
tronic stimulator showing my new design;

FIG. 2 is a front view thereof;

FIG. 3 is a left side view thereof;

FIG. 4 is a rear view thereof;

FIG. 5 is a top plan view thereof; and

FIG. 6 is a bottom view thereof.

It is to be understood that the appearance of the side
opposite that shown in FIG. 3 is the mirror image of the
view shown in FIG. 3.
